UNITED STATES PATENT OFFICE

CHARLES CAMPBELL, OF LONDON, ENGLAND, ASSIGNOR TO THE TABULATING MACHINE COMPANY, OF NEW YORK, N. Y., A CORPORATION OF NEW JERSEY

CONTROLLING MECHANISM FOR RECORD-CARD-CONTROLLED STATISTICAL MACHINES

Application filed December 17, 1926, Serial No. 155,538, and in Great Britain January 9, 1926.

This invention relates to record-card-controlled statistical machines of the kind which include controlling means operated by the record-cards (irrespective of the perforations therein) for maintaining the machine in operation while the record-cards are being fed through the machine and for stopping the machine (or bringing about a change in the operation thereof) after the passage of the last card or upon the passage of a suitably shaped stop-card.

Hitherto in such controlling means it has been customary to employ what is known as a "card-lever," which is a pivoted cam-lever held by a spring in the path of the cards and moved mechanically by the cards into a new position, thereby closing or opening a switch or switches or bringing about some other controlling operation.

It has been found that there is a limit to the number of switches which can be operated satisfactorily by such a card-lever, as the resistance offered by the lever to the passage of the cards is unduly increased, and there is a risk of injury to the card. Moreover, the card-lever and its mounting occupies an undesirable amount of space in the width of the card, thus reducing its capacity.

One of the chief objects of the present invention is to replace the card-lever by a controlling device which is without these disadvantages.

According to this invention a card-operated controlling device includes a pair of electric contacts located in the path of the record-cards and constructed and arranged to be separated by the record-cards to break a controlling circuit and to make contact to complete the circuit when no card is present, or when a suitably shaped stop-card is present.

It will be appreciated that the controlling circuit can be employed, by means of relays and the like, to effect a large number of controlling operations without in any way increasing the resistance offered to the passage of the card, and also that the said electric contacts (hereinafter referred to as card-contacts) can be made to occupy much less space than the card-lever hitherto used. In

fact it is preferred to employ a pair of contacts identical with the card-reading electrical contacts which co-operate with the holes in the card, these extra contacts being located to register with that part of the card which lies between one of the extreme columns of hole-positions and the adjacent lateral edge of the card. Thus the whole width of the card is available for record-perforations.

In order to avoid the formation of arcs at the card-contacts, and the consequent risk of injury thereto and to the cards, a shunt is provided across the card-contacts which shunt contains an automatically operated switch timed to close before each card leaves the said contacts and to open just after the next succeeding card has separated the contacts.

Referring to the accompanying drawing: 70
Figure 1 is a circuit-diagram of a machine embodying the invention, and
Figure 2 is a timing-diagram.

The motor circuit 10 contains stop-keys 11, 12 and a starting-key 13 of the usual form. 75
One of the stop-keys is manually controlled, and the other is operated automatically by the descending support for the cards which have passed through the machine when this support reaches its limit of downward movement. The starting-key is shunted through a holding relay 14 and the shunt contains the contacts 15 of a motor-control relay bridged by an automatically operated switch 16 timed to close when the No. 3 hole-position of a Hollerith card is at the reading-brushes and to open when a point on the next card between No. 9 and No. 8 positions is at the reading brushes, as shown in Figure 2.

It should be mentioned that the cards are fed to the brushes in such a way that the hole-positions pass the brushes in the order 9, 8 . . . 2, 1, 0.

Upon depressing the starting-key the holding relay contacts 14 close and if the starting key is released the running of the motor TM will depend upon the combined operation of the motor-control relay 15^a and the switch 16 and if the contacts 15 of this relay open, the motor circuit will be broken at a point 100

between positions 9 and 8 when the switch 16 opens.

The winding 15^a of the motor control relay is in what will be termed an intermediate circuit 17 which contains the contacts 18 of an "inverted" relay (that is to say one which opens when its winding is energized and closes when it is de-energized) two automatically-operated switches 19 and 20, and the winding 21 of a holding relay which when energized closes a shunt 21^a by its contacts 21^b across the switch 20 and the contacts 18 of the inverted relay.

The switch 19 is timed to close immediately after the leading edge of each card has reached the card-reading brushes and to open just after the last hole-position on that card has left the brushes.

The switch 20 is timed to close just before the trailing edge of each card leaves the brushes and to open when No. 8 hole-position on the next card is at the brushes.

The winding 18^a of the inverted relay is in a circuit 22^a, 22^b and 22^c termed the card-contact circuit, which includes a pair of contacts 23, 23^a arranged in the path of the card near one of its lateral edges and between the said edge and the adjacent column of hole-positions. Conveniently these contacts may be identical in form with the card-reading brushes 24 and contact rings 24^a there being a row of forty-six such brushes and contact rings, forty-five of which are used as card-reading contacts and the forty-sixth 23, which does not register with any holes in the cards, is used for the purposes of the present invention. The arrangement of the brushes and contact rings is described in British patent specification No. 23,566 of 1914.

These card-contacts are bridged by a shunt 25 containing an automatic switch 26, which opens just after the leading-edge of each card reaches the brushes and closes at the 5 hole-position of the same card.

It will be appreciated that the intermediate circuit 17 must be maintained closed in order to keep the motor running; if this circuit is broken the motor will stop.

Normally, therefore, it is necessary for continued running that the contacts 18 of the inverted relay should be closed (or if they open, that the shunt 21^a across it and the switch 20 should be closed as an alternative path) during the time that the switch 16 is open. When the first card of a series separates the controlling card-contacts 23, 23^a the inverted relay winding 18^a is de-energized and its contacts 18 close. The switch 20 is still closed at this time, and the switch 19 closes immediately afterwards. The intermediate circuit 17 is thereby completed, the motor control relay magnet 15^a is closed, and the motor circuit 10 is maintained closed as already explained.

The holding relay magnet 21 in the inter-

mediate circuit will close its contacts 21^b and close the shunt 21^a and the said intermediate circuit will then be under the joint control of the inverted relay contacts 18 (together with the switch 20 in series therewith) and the switch 19. 70

When the trailing edge of any card leaves the controlling card-contacts 23, 23^a the latter come together and complete the card-contact circuit 22^a, 22^b, 22^c energizing the inverted relay winding 18^a before the switch 19 has closed. Thus the inverted relay contacts 18 are opened, the motor-control relay winding 15^a is de-energized, and the motor would stop were it not for the fact that the switch 16 has not yet opened. Before this switch opens the card-contacts are separated by the next card, the switch 19 closes, the shunt 21^a across the switch 20 and the inverted relay contacts are closed by the holding relay 21 and the intermediate circuit is re-established, and remains so notwithstanding the subsequent opening of the switch 20. 80

If however no card appears as a consequence of the supply being exhausted the card-contacts 23, 23^a remain closed (and the inverted relay contacts 18 remain open in consequence) and the closing of the switch 19 is therefore powerless to close the intermediate circuit 17 because the contacts 21^b of the holding relay magnet 21 for the shunt 21^a have not been closed. Consequently the motor-control relay contacts 15 will not be closed, and when the switch 16 opens the main relay winding will be de-energized and the motor will stop. 95

The switch 20 plays no part in this operation, as will be appreciated, since it is in series with the inverted-relay contacts 18 and as the latter do not close again after the passage of the last card the intermediate circuit would remain broken in any case. Since the holding-relay contacts 14 open as soon as the switch 16 opens, the motor-circuit can only be re-established by depressing the starting key 13. 105

The machine will also stop on the passage of a stop-card. This stop-card has a narrow portion cut away from that one of its lateral edges which encounters the controlling card-contacts, such cut-away portion extending from its leading-edge to the 5 hole-position. Thus when a stop-card is feed to the brushes the card-contacts 23, 23^a will not be separated, the relay contacts 18 will remain open and the motor circuit will be broken as already explained, and the holding-relay contacts 14 will open. 115

The brushes 24 are mounted on a common bar 24^b and are supplied with current through the switch 19, 20 and the inverted relay-contacts 18 by means of a wire 24^c. The brush 23 is also carried by the bar 24^b but is insulated therefrom. The current is 125 130

taken from the rings 24^a by brushes 27 from which extend the usual counter-magnet circuits 28. The counter-magnets are shown at 29, and this part of the machine need not be described in detail as it is well known to those skilled in the art to which the invention relates.

It will be appreciated that when the intermediate circuit is broken as hereinbefore described no current is supplied to the brushes 24. If this circuit is broken by the passage of a stop-card, the switch 20 serves to cut off the supply of current to the brushes during the passage of the index-points on the 15 card past the brushes. Thus, if such a stop-card is provided with holes, as is sometimes the case to assist in sorting them into their correct positions in a stack of cards, these holes will not cause the counters to be operated.

The motor T M drives, through gearing 30, the feed-rolls 31 which advance the cards 32 past the brushes 24, the cards being fed to the rolls one at a time from a stack 33 25 by means of a picker 34. A shaft 35, driven at the rate of one revolution per card cycle, carries the rotary components of the switches 16, 19, 20 and 26, and another shaft 36 carries the contact-rings 23^a, 24^a. The gearing 30 is shown in a purely diagrammatic manner in Figure 1, no attempt having been made to represent the gear-ratio correctly.

The circuits 10, 17, 22a, 22b, 22c, 25, 28 are all supplied through leads 37, 38 and a 35 switch 39 from a source 40 of current.

The automatically-operated switches hereinbefore referred to are preferably arranged in the form of one or more rotary disc distributors driven in synchronism with the card-feeding means, each switch being provided by an arcuate distributor-segment of definite angular extent and position to make and break contact with a fixed brush at the required times. The distributors may be provided 45 with inserted bodies of glass or like material as described in the specification of my co-pending British Patent No. 269,622.

The diagram Figure 2 represents the timing of the various switches. The hole-positions and other points of reference on the card are shown extended horizontally and the times during which the various switches 50 are closed are represented by straight lines.

The letter D represents the position in 55 which the leading edge of a card just separates the brushes from the contact-rings, and is the position in which the machine stops. The letter B indicates a position just beyond the last or "0" hole-position on the card.

60 It will be appreciated that the full current is never actually interrupted at the card-contacts by the leading-edge of a record-card or the part of a stop-card not cut away, because the switch 26 in parallel therewith has closed 65 before the card-contacts are separated. This

switch moreover is always closed at the time the card-contacts come together. Consequently, no appreciable arcs are formed at the card-contacts, and the edges of the cards are not liable to be damaged as they would 70 be if the full current were interrupted at the card-contacts.

I claim:

1. In a record card controlled statistical machine, a card operated controlling device 75 comprising a pair of electrical contacts arranged in the path of record cards and arranged to be separated by the record cards to break a card contact circuit and to make contact to complete the circuit when no card is present, a control circuit including a motor control relay, an inverted relay in serial connection with said card contact circuit, the contacts of the inverted relay being in serial connection with the control relay and machine 80 controlled contacts for preventing the opening of said control circuit when a card is in cooperation with the card contacts.

2. In a record controlled statistical machine, a card operated controlling device comprising a pair of electrical contacts and arranged to control an inverted relay the contacts of which are in serial connection with a control relay the contacts of the latter being adapted to control the operation of the motor 90 of the machine, and cam operated contacts in serial connection with the contacts of the inverted relay adapted to close after each card has separated the aforesaid card contacts and to open before the card leaves the contacts 95 and permits them to close.

3. The invention according to claim 2 wherein supplemental contacts are in series with the inverted relay contacts timed to open after the cam operated contacts have closed 105 and to remain open until near the end of the card cycle.

4. In a record card controlled statistical machine including card reading contacts for analyzing the perforations of successively fed cards, a card operated controlling device adapted to control an inverted relay the contacts of which are in serial connection with a motor control relay in a supplemental circuit, cam contacts in serial connection with said 110 inverted relay contacts, said card reading contacts being in serial connection with the inverted relay contacts and the cam contacts whereby current is supplied to the card reading contacts in accordance with the opening 115 and closing of said cam contacts and the inverted relay contacts.

5. In a record card controlled statistical machine comprising means for successively feeding record and stop cards to analyzing brushes, a control circuit adapted to control said means, and a controlling device for said control circuit comprising a pair of electrical contacts adapted to cooperate with said successively fed cards whereby said contacts are 125 130

separated by the record cards to break the control circuit, and to make contact to complete the control circuit when a suitably shaped stop card is present and contacts in the circuit which controls said feeding means opened and closed in accordance with the opening and closing of the control circuit, respectively.

6. In a record card controlled statistical machine comprising means for successively feeding record cards to an analyzing mechanism, a card testing device comprising a pair of oppositely disposed testing elements adapted to be physically contacted by opposite sides of the record cards to provide for a relative separation of said testing elements, means whereby the continuity of the operation of the card feeding means is dependent upon the relative separation of the testing elements by a series of successive cards, and means comprising machine operated contacts for permitting the continuity of the machine to the end of each cycle irrespective of the closure of the testing elements by the absence 25 of the card fed during that cycle.

7. In a record controlled statistical machine comprising means for successively feeding to analyzing brushes a series of perforated records the operation of which is effected independently of the presence of said cards, a control circuit (17) for controlling said means, machine operated contacts (19), and a pair of electrical contacts (23) cooperating with opposite sides of successively fed cards and separated by the record cards to close the control circuit (17) which is retained closed by the closure of the machine operated contacts (19) and to make contact when no cards are present to open the control circuit irrespective of the closure of the machine operated contacts at a certain point in the machine cycle.

In testimony whereof I affix my signature.
CHARLES CAMPBELL.
